ENGINE CYLINDER BLOCK WALL REBORING IMPLEMENT

Edward F. Svab, Hudson, Ohio

Application July 19, 1935, Serial No. 32,301

1 Claim. (Cl. 77—75)

This invention relates to a cylinder block wall reborining implement for engines.

The primary object of the invention is a novel design of an implement of the character referred to that permits very light construction so that it is light to handle, convenient to manipulate and easy to adjust.

A further object of the invention is to provide an implement of the character referred to that allows the cylinder block of an engine to be reborined without removing the cylinder block from the chassis of an automobile.

Further objects of the invention are to provide a device of the character referred to that accommodates a change of one size to another in a comparatively short time, that does not require the walls of the cylinder to be polished after the reborining operation, that is highly efficient for its intended purpose and comparatively inexpensive to manufacture and operate.

With the foregoing and other objects in view the invention consists in the novel construction, combination and arrangement of parts as will be hereinafter more specifically described and illustrated in the accompanying drawings wherein is disclosed an embodiment of the invention, but it is to be understood that changes, variations, and modifications may be resorted to without departing from the spirit of the claim hereto appended:

In the drawings wherein like reference characters denote corresponding parts throughout the several views:

Figure 1 is a top plan view of the reborining implement constructed in accordance with the present invention.

Figure 2 is an end view at the upper end thereof.

Figure 3 is a diametric sectional view taken substantially on line 3—3 of Figure 1.

Figure 4 is a diametric detailed sectional view taken substantially on line 4—4 of Figure 1 and looking in the direction of the arrows.

Figure 5 is an enlarged perspective view of the upper end of the mandrel with parts thereof removed.

Figure 6 is a fragmentary perspective view of an end of one of the stabilizing blocks.

Figure 7 is a perspective fragmentary view of the blade.

Referring to the drawings in detail 10 indicates generally a hollow cylindrical mandrel of uniform diameter and open at each end. It will be noted as the description proceeds that the construction of the implement admits of a very light implement easy to handle and well balanced, and in

keeping with this purpose the thickness of the walls of the mandrel are considerably reduced, from the customary practice. The length of the mandrel from one end to the other should be such as will be slightly longer than the cylinder blocks used in internal combustion engines for automobiles. There is a blade receiving slot 11 in the mandrel which extends from a point adjacent one end thereof to a point adjacent the other end thereof. The slot 11 extends throughout the major portion of the mandrel. There are a pair of spaced longitudinally extending support bars 12, 13 secured by the screws 14 to the outer face of the mandrel one to each side of the slot. The space between the confronting faces 15 of the support bars registers with the slot 11. The bars 12, 13 are substantially coextensive with the length of the slot and the confronting edges 15, 16 respectively of the bars are parallel and disposed on a bias with respect to the diameter of the mandrel. The space between the confronting edges of the bars forms a tight sliding fit with the opposed faces of the blade as will hereinafter appear. The heads of the screws 14 are countersunk with respect to the outer faces of the bars. 25 The blade 17 is an elongated bar which seats edgewise in the space between the supporting bars 12, 13 and the inner end thereof extends into the slot 11 so that the blade may be adjusted radially as will hereafter appear. The slant 30 of the blade is in a direction away from the travel of the mandrel and the cutting edge 18 thereof is along the corner of the blade. The trailing portion of the blade is provided with the usual clearance.

Longitudinally extending stabilizing blocks 19, 20 are secured to the outer face of the mandrel by means of screws 21 the heads of which are countersunk in the outer face of the blocks. The blocks 19, 20 extend the major portion of the 40 length of the mandrel 10 and are circumferentially spaced at points substantially equidistant from the blade support and from each other. The outer surface of the blocks are rounded so that when they rub the wall of the cylinder 45 being reborined they will not injure the same.

Reinforcing rings 21, 22 are secured inside of the mandrel by means of the screws 23 one adjacent each end of the mandrel. The reinforcing rings are positioned so that the ends of the 50 blades bear on the major portion of the outer periphery. In each reinforcing ring there is a radially supported set screw 24 the head of which extends into the interior of the mandrel and the end of the shank bears against the inner edge 55

of the blade 17. Near the upper edge of the mandrel and outwardly of the reinforcing ring 21 the diametrically opposed walls are formed with round openings 25 which receive the round bar 5 26 that is used for a handle in turning the mandrel when the walls of the cylinders are being reborbed.

In using the refacing implement of the present invention the end of the mandrel away from the 10 handle 26 is inserted in the top of the cylinder first. The blade 17 should then be adjusted by the set screw 24 until they touch the walls of the cylinder to be reborbed. When the blade has been adjusted to touch the wall the mandrel is 15 turned in a clockwise direction with respect to Figure 2 by the handle 26. It has been found by experience that the blade should never be extended above the face of the supporting blocks beyond one quarter of an inch. If it is necessary to extend the blade further than one quarter of 20 an inch it is necessary to change the stabilizing blocks 19, 20 and apply thicker or higher blocks. In other words, in reborbing cylinders customarily used in automobile engines the height of the 25 stabilizing block should never allow any greater clearance between the blocks and the cutting edge 18 of the blade of more than one-quarter of an inch.

When the end of the mandrel is inserted to a 30 point where the blade begins to resurface the cylinder the construction of the implement in accordance with the present invention requires very little downward pressure beside the turning

of the mandrel. It has been found that the turning of the mandrel will cause the same to progressively move axially of the cylinder under its own weight.

Having described my invention, what I claim is: 5
A manually operated cylinder block reborbing implement comprising an elongated sleeve mandrel equipped with a continuous slot extending through the wall and in an axial direction along the major portion of the length intermediate 10 the ends of said sleeve, a pair of elongated spaced blade supporting bars, of a length substantially equal to the length of the slot, said bars being secured to the outer periphery of the sleeve one on each side of the slot and having the 15 space therebetween registering with said slot, the confronting edges of the bars being parallel and disposed at an angle relative to the diametric plane of the sleeve passing through the slot, an elongated blade of a length substantially equal to 20 the length of the slot and seated edgewise therein, said blade extending outwardly from the slots through said space and having a tight sliding fit between the confronting edges of the supporting bars, reinforcing members inside the sleeve, 25 radially disposed adjusting screws carried by the reinforcing members and having their outer ends bearing against the blade to adjustably support said blade, and spaced stabilizing blocks mounted on the periphery of the sleeve in spaced relation 30 to the supporting bars.

EDWARD F. SVAB.
